UNITED STATES PATENT OFFICE.

FREDELLIA H. MOYER, OF CANTON, OHIO.

METHOD OF JOINING SERRATED STEEL STRUCTURAL UNITS.

Application filed September 21, 1926. Serial No. 136,812.

The invention relates to structural members such as beams, joists, columns, struts, purlins and the like, and more particularly to such structural members in which the web portion contains considerably less material than the ordinary rolled sections now in common use.

The object of the improvement is to provide rolled steel sections such as I-beams, channels, angles, T-bars or rolled steel plates and the like, with perforated or open work webs containing less material and of greater depth and strength than in the usual rolled sections.

Commercial hot rolled I-beams, channels and similar structural shapes such as are used in standard building construction, include web members of solid material integrally formed with the flanges throughout the entire length of the beam, channel, or other sections; this being necessarily due to the fact that these structural members are rolled from a single piece of steel by a method of rolling wherein it is impossible to produce the section as a single piece without the solid integral web portion.

In built up sections such as plate steel girders and the like, the web member is also of solid plate material extending throughout the entire length of the girder.

In all such solid web units there is a considerable excess of material in the web portions, over that actually required for transmitting stresses from flange to flange, and this invention contemplates the reduction of this excess weight as far as possible, by cutting the web portion of the beam or other structural member into two parts longitudinally, the cut being started at a point on or between the median line of the web and one flange and following a path away from and returning to the line of the starting point, continuing regularly back and forth throughout the entire length of the web, cutting the beam into two substantially matched serrated halves.

These serrated halves of the beam or other sections are then placed together with the high points of the serrations of each half abutting the high points of the other half, the abutting portions of the web being attached together as by welding, forming a beam or the like of greater depth than the rolled section from which it is formed, and having considerably less material in the web portion.

An embodiment of the invention is illustrated in the accompanying drawings forming part hereof, in which

Figure 1 is a side elevation of an eight inch I-beam in which the cutting lines are shown to produce the serrated sections for re-assembling to produce a twelve inch beam;

Fig. 2, is a similar view of the twelve inch beam formed from the sections cut as shown in Fig. 1;

Figs. 3 and 4, are views similar to Figs. 1 and 2, showing the loss of material necessitated where the transverse cut, shown in Figs. 1 and 2, is not made;

Figs. 5 and 6 are side elevations of I-beams showing cutting lines formed in the webs thereof to produce the wider beams shown in Figs. 7 and 8 by placing together one half of each of the beams shown in Figs. 5 and 6;

Fig. 9 is a perspective view of a beam constructed in accordance with the invention, showing vertical web stiffeners in the form of angle irons or the like;

Fig. 10 is a perspective view of a beam showing a modification of the serrations;

Fig. 11 is a perspective view showing an application of the invention to the web of a built up plate steel girder, the flat web plate being serrated and re-assembled to form a girder of greater depth and strength than would be obtained using the same width web plate not serrated and re-assembled;

Fig. 12, is a side elevation showing the application of the invention to a structural member with latticed or reticulated web;

Fig. 13 is a transverse section of the same, and

Fig. 14 is a perspective view of the beam shown in Fig. 2.

Similar numerals refer to corresponding parts throughout the drawings.

In Fig. 1 is shown an I-beam having the flanges 1 and web 2. For the sake of illustration it is assumed that this is an eight inch beam. In carrying out the invention the web is cut upon a line indicated at 3, starting at one end of the web, at one side of the median line thereof, as indicated at 4.

The point 4 may be substantially six inches from the lower flange, and the cut extends back and forth across the median line of the web, preferably having the angular portions 5 and straight portions 6, parallel with the flanges of the beam.

The beam is thus divided into two halves,

each having one flange and a serrated web. The upper half may then be divided, by the transverse central cut 7, into two similar portions indicated at A and B, while the 5 lower half is indicated at C.

The portions A and B of the upper half are then removed and placed in reverse position, upon the lower section C, as shown in Fig. 2, the high points of the serrations of 10 each half abutting the high points of the other section, as shown at 8, forming intervening open spaces 9, while the two outer ends of the sections A and B meet at the transverse center of the beam as shown at 10. 15 The points 8 and 10 are then connected together as by welding, producing a twelve inch beam having the same amount of material which was originally in the rolled eight inch beam, but with greatly increased 20 strength.

In Figs. 3 and 4 is shown a beam formed in the same manner as in Figs. 1 and 2, excepting that the transverse cut is not made to divide the upper half into two sections. 25 The beam shown in Fig. 3 is cut in the same manner as in Fig. 1, upon the line 3, forming the upper section D and lower section E. The upper section is then removed and placed upon the lower section, being moved 30 one-half of a space to the left, as shown in Fig. 4, the abutting points of the two sections being welded together as above described, and the projecting end portions indicated in dotted lines at 11 and 12, being 35 then cut from the upper and lower sections respectively. This forms substantially the same beam as in Fig. 2 but requires the wasting of the material in the cut off ends 11 and 12. 40 As shown in Figs. 5 and 6, two similar I-beams may be reversely serrated upon the lines 3^a and 3^b respectively, forming the top and bottom sections F and G from the beam in Fig. 5, and the top and bottom sections 45 H and I from the beam shown in Fig. 6. The bottom section G and top section H may then be matched to produce a beam with closed ends, as shown in Fig. 7, and the bottom section I and top section F may be similarly matched to produce a beam with open 50 ends, as shown in Fig. 8.

If it is desired to provide closed ends upon the beam such as shown in Fig. 8, angle iron braces or the like, such as are shown in 55 Fig. 9, may be welded to the ends of this beam, although for some purposes this may not be necessary.

Fig. 9 shows a beam which may be made in any of the manners above described, in 60 which vertical web stiffeners such as the angle irons 13, may be welded across the beam at intervals, such web stiffeners being particularly desirable where the web is of considerable depth in comparison with the flange width.

In Fig. 10 is shown a modification in which the serrations may be substantially square, as shown at 14, the invention being otherwise carried out in the manner above described, and the two halves welded together to produce a beam of greater depth 70 and strength.

Fig. 11 shows an application of the invention to the web of a built up plate steel girder, in which the flat web plate 15 is serrated as above described, and the sections then re-assembled in the manner outlined above as a part of the complete unit.

Figs. 12 and 13 show the invention applied to a lattice or reticulated web girder, 80 in which the top and bottom chords 16 and 17 respectively are parts of an I-beam serrated as above described, the serrations 18 thereof being utilized as receiving parts to which the lacing members, in the form of 85 angle irons 19, are attached.

It is obvious from the above that by serrating the web of a beam or the like and abutting the serrations or high points of the sections thus formed, or separating them, 90 the depth of the original beam is increased, providing corresponding open spaces between abutting or opposite points of the web member. The increasing of the depth of the beam is also accompanied by a marked 95 decrease in the amount of material in the combined web member, with a corresponding decrease in its weight relative to the depth of the beam.

This method of web serration may be applied to the various standard structural rolled sections such as I-beams, channels and the like, including former solid web steel girders wherein the solid web member may be divided into two serrated portions and 100 assembled as an open web girder in the same manner that the beam sections are assembled.

I claim:

1. The method of forming beams and the 110 like, which consists in separating the solid web portion of a beam by a serrated cut, cutting one of the sections thus produced transversely into two parts, reversing the position of said parts, and matching the sections together to produce a beam of greater depth.

2. The method of forming beams and the 120 like, which consists in separating the web portion of a beam by a serrated cut; cutting one of the sections thus produced transversely into two parts, connecting the outer ends of said parts together and matching the sections to produce a beam of greater depth.

3. The method of forming beams and the 125 like which consists in separating the solid web portion of the beam by a serrated cut, cutting one of the sections thus produced transversely into two parts, reversing the position of said parts and matching the sec- 130

tions together to produce a beam of greater depth and connecting vertical web stiffeners across the beam at intervals.

4. The method of forming beams and the like, which consists in separating the web portion of a beam by a serrated cut, cutting one of the sections thus produced transversely into two parts, connecting the outer ends of said parts together and matching the sections to produce a beam of greater depth, and connecting vertical web stiffeners across the beam at intervals.

5. A beam or the like formed by cutting the web of a beam or the like upon a line which alternately crosses the median line ¹⁵ thereof, cutting one of the sections thus produced transversely into two parts, and reversing the position of said parts, the serrations of the web portions being abutted and connected together. ²⁰

In testimony that I claim the above, I have hereunto subscribed my name.

FREDELLIA H. MOYER
